ERNEST PARSONS, OF SPRINGFIELD, MASSACHUSETTS, ASSIGNOR TO THE CARLING TOOL & MACHINE CO., INC., OF HARTFORD, CONNECTICUT, A CORPORATION OF CONNECTICUT

MOP OR BRUSH HOLDER

Application filed December 4, 1931. Serial No. 573,991.

This invention relates to an improved mop or brush holder and to holders for household cleaning utensils of the general character of mops and brushes. The idea of the 5 invention is to manipulate the holder parts with improved convenience and simplicity. This is particularly important to the household worker.

The way in which this idea is carried out 10 will be clear from the annexed drawing and following description:

In the drawing:

Fig. 1 is a partial sectional view at the 15 clamping end of the holder with the parts in position to hold the frame of a brush, mop, or the like;

Fig. 2 is a view similar to Fig. 1 with the parts in position to release the frame of the 20 brush, mop, or the like;

Fig. 3 is an end view of one of the parts; 25 Fig. 4 is an end view of the spring part;

Fig. 5 is a sectional view of one modification;

Fig. 6 is a plan view of another modification; 30 Fig. 7 is a plan view of the part shown in Fig. 3.

The preferred form of the invention is 35 shown in Figs. 1 and 2. The parts are designed so that they can all be made of sheet metal. Part 1 is provided with means at one end to receive a handle in any usual way as by a socket or other means of attachment, as by a spear head or insertion in a 40 wooden handle body. The clamping end of part 1 is preferably flattened out as a plate 2. The part 3 is made up of a metal stamping with side ears 4, trough-shaped end 5 and specially shaped opening 6 (see Figs. 3 and 45 7). The part 7 is a flat spring with one end attached permanently to part 1 and so that the other end 7' may fit in the larger part of opening 6 (see Fig. 7) and be flush with the surfaces of part 3 as in Fig. 1. The fitting end of the spring may be readily pushed 50 out of the plane of part 3. Then parts 2 and 3 are relatively slidable but without separation. The ears 4 and the bent portion of the spring 7 (which can pass through opening 6 at all positions of the parts) con-

trol the relative movements. The result is that such movements of parts 2 and 3 are restricted to a limited sliding movement in a straight line and of enough scope to move a trough-shaped end 5 completely under 55 and completely outside of part 2. This is indicated by the difference between the parts shown in Figs. 1 and 2.

When it is desired to release a mop frame it can be done by grasping the holder at 60 the side ears 4, pressing spring 7 down and pulling part 2 backwardly. The parts will then change from the positions of Fig. 1 to those of Fig. 2. In the latter the trough-shaped end 5 is open at the top and the 65 frame 10 of the mop or the like can be lifted out. When it is desired to put the mop in the holder it can be done by merely placing frame 10 in trough end 5 and pushing the two parts 3 and 2 together. When the parts 70 move from the position of Fig. 2 to that of Fig. 1, it is not necessary to handle the spring 7 in any way because it will snap into holding position automatically as the two parts are slid together.

In Fig. 5 I have shown a modification in which the flat spring is omitted and a spring pressed button 11 substituted therefor. The operation is substantially the same; the button 11 is pressed down to carry the head 12 80 out of the plane of the part 13 in which there is an opening to fit head 12 with a narrower extension 14 of the opening rearwardly to receive the shank of button 11 as part 13 moves relatively to part 2.

In Fig. 6 I have shown another modification in which part 20 is hinged to part 1 at 22. Its trough-shaped end 25 can be swung to open position as shown, or to position for trough end 25 to underlie the frame 90 and transversely. A spring pressed button 30 like button 11 can in cooperation with a slot like 32 lock part 20 in position with the trough 25 in mop holding position or release part 20 to swing into mop releasing 95 position. The operation is much the same as the parts in Fig. 5 except that there is a pivoted instead of a sliding movement of the parts for separation.

In all these modifications there is one 100

important feature in common. It is the arrangement by which a spring pressed catch is operable into and out of the plane of a movable part on the end of the holder to lock the holder into mop holding position and to release it for a simple slidable or rotatable movement out of such position into mop releasing position and in the latter position the holder presents a trough-shaped end in full view for the reception to or removal of the mop frame from the holder. This feature makes a simple, inexpensive, easily operable device that appeals to the user.

15 The form of the invention best known to me at this time is that shown in Figs. 1 and 2. It is composed of only three parts, each made of metal stampings, is produced at a minimum cost, and is the simplest form both 20 for making and for use.

Having described my invention in detail, its scope is pointed out in the following claims:

1. A holder for mops, brushes and the like 25 comprising in combination, a metal frame member having one end adapted for attachment to a handle, and the other end to a frame of the mop, brush, or the like, a co-operating member associated with and 30 slidable relative to said other end and having an open ended trough-shaped portion adapted to be closed at the top by a portion of said other end of the frame member, and a spring pressed catch associated with the 35 metal frame and adapted to hold said frame and co-operating member against relative sliding movements when the trough is closed at the top by the frame member.

2. A device of the character described including two flat plates having means associated therewith to facilitate relative longitudinal sliding movements, and a spring member attached to one plate with a free end adapted to normally rest under spring 40 pressure in a corresponding opening provided in the other plate to hold the two plates against sliding movements, one of said plates having a trough-shaped end portion in position to be covered and uncovered 45 at the top by the other plate for holding and releasing a frame of a mop or the like, said spring member being movable to release the plates for sliding movements and to automatically lock the parts together when 50 the trough-shaped end portion in one plate is covered by the other plate.

3. In a holder for the use described, a sheet metal part of one piece having a transverse trough at one end and provided with 55 an opening through the bottom having a connected and smaller opening extending rearwardly, a co-operating plate member adapted to slide relatively to said sheet metal part and to cover and uncover said trough, means to facilitate the relative slid-

ing movements thereof, and a spring pressed member fastened to the co-operating plate member and having a shank extending through said plate member with an end portion of larger size than the shank to lie 70 in said larger opening.

4. A holder for mops, brushes and the like comprising a metal frame having one end adapted for attachment to a handle and the other end to a frame of the mop, brush, or the like, the latter end being flattened, means having side ears to receive the flattened end in slidable relation and also having an open ended trough-shaped portion adapted to be closed at the top by the flattened end, and a spring pressed catch fastened to the metal frame and adapted to hold said frame and means from relative sliding movements when the trough is closed at the top by the frame.

5. A device of the character described comprising two flat plates having interfitting parts to facilitate relative longitudinal sliding movements, and a flat spring attached to one plate with a free end adapted to normally rest under spring pressure in a corresponding opening of the other plate to hold the two against sliding movement, one of said plates having a trough-shaped end portion in position to be covered and uncovered at the top by the other plate for holding and releasing a frame of a mop or the like, said spring being movable to release the plates for sliding movements and to automatically lock the parts together when the trough-shaped end portion in one plate is covered by the other plate.

6. In a holder for the use described a sheet metal part of one piece having a transverse trough at one end, an angle guide on each side rearwardly of the trough and an opening through the bottom having a connected and smaller opening extending rearwardly, a cooperating plate member fitting in said guides and adapted to cover and uncover said trough, and a spring pressed member fastened to the cooperating plate member and having a shank extending through said plate member with an end portion of larger size than the shank to lie in said larger opening.

In testimony whereof I have affixed my signature.

ERNEST PARSONS.
